CLAIM

The ornamental design for a cremation urn, as shown and described.

DESCRIPTION

FIG. 1 is a front view of our new, original and ornamental design for a cremation urn, the back view, left side view, and right side view thereof being the same shape as the front view, the pattern of the surface ornamentation repeats around the circumference of the cremation urn.

FIG. 2 is a top view thereof.

FIG. 3 is a top view of a second embodiment of our new, original and ornamental design for a cremation urn, the front view, back view, left side view, and right side view thereof being the same shape as FIG. 1.

The unshown portions of the article form no part of the claimed design.
